CROSS-FEED MECHANISM FOR GRINDING MACHINES

Roger S. Pyne, Longmeadow, and Edward A. Allen, Westfield, Mass., assignors to Van Norman Company, a corporation of Massachusetts

Application January 23, 1943, Serial No. 473,352

7 Claims. (Cl. 74—290)

This invention relates to cross feed mechanism for grinding machines and the like, and has for its object the provision of cross feeding mechanism which will give a slow continuous feeding motion adjustable in rate by altering the speed of the driving element, and which will give a rapid return motion by a mere reversal of the driving element without changing its rate. A further object is to provide such a mechanism with means whereby the cross feed may be subjected to hand control at any time and in either direction merely by rotating a hand control, and in which the rotation of said control serves automatically to cut off the cross feed from its power drive whereby manual operation is rendered easier. A further object is to provide a differential or epicyclic drive for a cross feed with means for locking the epicyclic train when the driving element is reversed. A further object is to provide a cross feeding mechanism power driven through a friction clutch and having a manual control; in which mechanism is provided to reduce the drag of the friction clutch when the manual control is operated. A further object is to provide a compact cross feeding mechanism capable of being driven from a variable speed motor. Additional objects will appear from the following description and claims.

Referring to the drawings,

Fig. 1 is a front elevation of a portion of the bed of a grinding machine embodying our improved cross feeding mechanism;

Fig. 2 is a top plan thereof with certain parts removed;

Fig. 3 is a detail section of parts appearing in Fig. 4 but taken in a plane at right angles to the plane of the latter figure;

Fig. 4 is a section on line 4—4 of Fig. 1;

Fig. 5 is a section on line 5—5 of Fig. 4 with the parts in a neutral position;

Fig. 6 is a section on line 6—6 of Fig. 5 with the parts in feed position;

Fig. 7 is a view similar to Fig. 5 showing the parts in feed position;

Fig. 8 is a similar view showing the parts in the position they occupy during reversal;

Fig. 9 is a view similar to Fig. 6 showing the parts in the position they occupy during reversal; and

Fig. 10 is an enlarged view corresponding to a portion of Fig. 1 but with part of the casing broken away to disclose the internal construction.

In Fig. 1 is shown a portion 10 of the frame of a grinding machine having a cross slide 11 carrying either the work or the tool. The grind-

ing machine may be adapted for cylindrical bore, or surface grinding, and the details of construction need not be shown as they will vary in a known manner in accordance with the nature of the work which the machine is intended to do. As is customary, the slide is provided with a nut (not shown) into which is threaded a feed screw 12. This screw is driven by the cross feed mechanism continuously in one direction at a slow rate to cause feeding movement of the slide, and at a relatively rapid rate in the opposite direction to cause a rapid return movement of the slide.

Power for actuating the cross feed is preferably secured from a reversible, variable-speed motor 13 which may be of any desired type. The shaft of this motor carries a worm 14 meshing with a worm wheel 15 forming part of a cage 16 rotating freely on a pair of ratchet-carriers 17, 18. Each of these carriers 17, 18 is freely rotatable on a sleeve 19 which in turn is rotatable on a driving sleeve 20. Through the sleeve 20, and coupled to it by a pin and slot connection 21, is a shaft 22 having at one end a pinion 23 meshing with a gear 24 on the feed screw 12. Cage 16 has a pivot shaft 25 secured therein which carries, preferably on needle bearings 26, a pair of connected gears 27, 28 meshing respectively with gears 29, 30 on the ratchet-carriers 17, 18.

Ratchet-carrier 18 has a gear-toothed ratchet 31 formed thereon which coacts with a pawl 32 pivoted at 33 to the housing 34 of the cross feed mechanism and pressed towards and away from the ratchet by a friction spring band 35 encircling a groove in the case 16 and having offset portions engaging a pin 35' on the pawl with a slight lost motion. The pawl holds the carrier 18 against rotation in one direction but permits it to rotate freely in the other. As will be pointed out below, rotation of the cage 16 in the direction of the arrow 36 (in which direction corresponding rotation of the carrier 18 will be prevented by the pawl) produces rotation of the screw 12 in the same direction at a feed rate; while rotation of the cage 16 in the opposite direction, as shown in Fig. 9 by arrow 37 (in which direction rotation of the carrier 18 will be permitted by the pawl), causes reverse rotation of screw 12 at a relatively rapid rate. Ratchet-carrier 17 carries a ratchet 38 (Fig. 5) coacting with a free floating pawl 39 pivoted to a friction spring band 40 encircling a groove in the ratchet-carrier 17 and actuated as will be described by pins 41 and 41' on cage 16. When the cage is driven by worm 14 in the feeding direction of arrow 42 the pawl 39

will be lifted by pin 41 so as to slip freely over the ratchet 38 (Fig. 7); but when the direction of the cage is reversed as in Fig. 8 the pawl will be pressed against the ratchet by pin 41' so as to drive the carrier 17 positively from the cage 16.

Carrier 17 has fixed to it an annular disk 43 so as to form an internal recess enclosing a pair of friction plates 44, 45. Plate 44 is formed on one end of sleeve 20, which as previously stated is pinned to the feed screw driving shaft 22. Plate 45 is slideable on shaft 22, has a sliding pin driving connection 46 with plate 44 and is pressed away from it by a spring 47. Normally the plates 44, 45 form a frictional driving connection between the carrier 17 and the sleeve 20 and shaft 22 of sufficient grip so that for all grinding operations the connection is for practical purposes rigid. It should be remembered that the amount of cross feeding movement per cycle is measured in thousandths of an inch or less, and that the power required for the feed is relatively small. The friction clutch mechanism is, however, capable of being made to slip when manual operation is desired, and in accordance with one feature of the invention the frictional drag is automatically decreased by the act of operating the manual drive, as will be described in detail below. Before going into that matter, however, it may be clearer to consider the manner in which the mechanism already discussed will operate in both forward and reverse directions.

Let first the worm 14 be driven in the feeding direction at a rate determined by the speed of the variable speed motor 13. For a roughing cut the motor will be driven at a relatively rapid rate, while for finish grinding the speed of the motor can be reduced by the use of suitable resistances and control elements which are standard in the use of motors of that type. Control of motor speed may be manual, or may be under the control of gauges, dogs, and the like as will be well understood by those skilled in the art, and may have any desired gradations between the first rough feed and the final slow finishing speed. As long as the direction of rotation of the worm 14 is in the feeding direction, however, the cage 16 will be rotated in the sense of the arrow 42 of Fig. 7. The ratchet and pawl connection 38, 39 will be disconnected by pin 41 in this direction of movement, so that the drive of the friction clutch is solely through the differential gears. As the cage revolves, the pivot shaft 25 is carried bodily with it, and the connected gears 27, 28 will be rolled around on gears 29, 30 formed on the carriers 17, 18. Since carrier 18 is prevented from rotation in this direction by the pawl 32, which is tilted into engagement with the gear-toothed ratchet 31 by the drag of cage 16 on the friction spring band 35, the pinions 27, 28 will be caused to rotate on their pivot shaft 25 as pinion 28 rolls around the then stationary gear 30, and carrier 17 will be rotated by the interengagement of pinion 27 with gear 29 at a relatively slow rate dependent upon the differences in the numbers of teeth in the two gear pairs. This will cause rotation of the friction clutch, and through it and the shaft 22 a rotation of the feed screw 12 at a slow rate.

If now the direction of rotation of the worm 14 be reversed the cage 16 will be rotated in the direction of arrow 49 in Fig. 8. Due to the action of the pin 41' on the pawl 39 the ratchet 38, the cage 16, and carrier 17 will move as a unit. Since there is in this case no relative movement between cage 16 and the gear 29 on carrier 17 the

pinion 27 must move bodily around the axis of shaft 22 without rotation on its own axis, and this of course carries pinion 28 in the same manner. Gear 30 will thus be rotated and the carrier 18 will turn in the direction of arrow 37 (Fig. 9), in which it is not impeded by the stationary pawl 32 since this pawl has been drawn out of contact with its ratchet as described. During this reverse motion carrier 18 is without function, the drive of shaft 22 being directly from cage 16 to carrier 17 and thence to the shaft through the friction clutch. It will be seen that this direct drive will be the same in speed as that of cage 16, whereas the forward motion of the cage produced a much slower rotation of the shaft through the differential gearing. Reversal of worm 14 is thus accompanied by reversal of the shaft 22 and automatically produces an increased speed of rotation of the latter. The reason for providing lost motion between the offset ends of spring band 35 and pin 35' is to permit a relief of pressure between the pawl 32 and the adjacent gear tooth before the pawl is rocked, thereby preventing the pawl from being jammed tightly before it can be rocked into an inactive position. The lost motion between pins 41, 41' and pawl 39 is shown as larger in amount, this being necessary because of the multiplying effect of the differential gearing, member 16 moving faster in feed than the member 18. While the exact mechanism shown may be varied, it is generally necessary to have some means for locking ratchet 31 against motion in both directions, as the differential gearing will develop a tendency to drive the carrier 18 unless the latter is locked. The friction drag mechanism described has proved in practice capable of performing this action satisfactorily.

Shaft 22 passes through a ball bearing 50 axially slideable in the housing, and has keyed to it a cam member 51. One end of the cam member abuts a collar 52 through which a thrust train is established through bearing 50 to the central portion of friction plate 45. The forward end of the shaft 22 has fixed to it a sleeve 53, between which and the hub 54 of a hand wheel 55 is a thrust bearing 56. Hub portion 54 and cam member 51 have one or more opposed depressions 57 (Fig. 3) receiving between them balls 58. The hand wheel normally has a slight free rotation relative to the shaft, although it revolves with it, but in proportion to its rotation a wedging action of the balls 58 on the walls of depressions 57 is developed which forces the friction plate 45 away from the plate 43 against the force of spring 47. At the same time the wedging action couples the shaft and the handle together. The combined result of these actions is that the mere act of rotating the hand wheel manually both couples it tightly to the shaft 22 and releases the friction clutch. In connection with the latter effect it should be noted that while the cams 51 act only to shift the friction member 45 the carriers 17, 18 have a limited sliding movement in an axial direction, so that the clutch action is maintained not by pressure of friction member 44 on the carrier 17 but rather by an expanding force created by the separation of the two friction plates by the spring 47. Sleeve 20 is held against axial movement by the right hand bearing 60, so that when axial pressure is directed against friction plate 45 it will be moved nearer to plate 44, which is held against movement by being a part of sleeve 20. The surfaces of members 16 and 43 against which the friction members act are, how-

ever, permitted slight axial movement, so that the pressing together of the friction plates will effectively relieve any pressure against the co-acting surfaces. The slight drag which may result from contact without pressure of members 17 and 44 will exert no retarding force on the manual operation of shaft 22 by means of the hand wheel.

A bushing 61 is mounted around the cam member 51 and has a conical bearing connection 62 therewith, against which it is pushed by a spring 63. The bushing thus can be adjusted around the shaft 22 as may be desired merely by pushing it in and turning it to the desired location. The bushing carries an abutment 64, preferably in the form of an eccentric which may be rotated to bring it to an inner inactive position, and contacts with a lever 65 controlling a conventional limit switch 66. If the eccentric is in its outer position the rotation of the shaft will carry the eccentric into contact with the lever 65 and will open the limit switch at the desired time as determined by the rotative adjustment of the bushing 61. This mechanism is desirable in some cases where control of the motor 13 by a size gauge in contact with the work is not desired, the limit switch 66 serving to open the motor circuit when the feed has progressed to a predetermined point.

What we claim is:

1. In a feed mechanism for machine tools, a reversible, variable speed driving element, transmission means between said element and said mechanism for driving the latter in feeding direction at a slow rate adjustable by alteration of the speed of the driving element, and means automatically operable to increase the speed ratio of said transmission upon reversal of the driving element without change in the rate of the latter, to drive said mechanism in the reverse direction at a rapid rate, means for manually driving said mechanism in either direction and means to automatically disconnect said transmission means upon actuation of said manual driving means.

2. In a feed mechanism for machine tools, a reversible, variable speed driving element, transmission means between said element and said mechanism, said transmission means including a differential through which the mechanism is driven in feeding direction at a slow rate and means for automatically locking said differential when the driving element is reversed to drive said mechanism in the reverse direction at a rapid rate without change in the rate of the driving element, means for manually driving said mechanism in either direction, and means to automatically disconnect said transmission means upon actuation of said manual driving means.

3. In a feed mechanism for machine tools, a shaft, a reversible, variable speed driving element, transmission means between the driving element and the shaft for driving the latter at a slow rate adjustable by alteration of the speed of the driving element, means automatically operable to increase the speed ratio of transmission upon reversal of the driving element without change in the rate of the latter to drive said mechanism in the reverse direction at a rapid rate without change in the rate of the driving element, a clutch between the shaft and transmission means, manual means for rotating the shaft and cam

means actuated by said manual means for disengaging said clutch upon actuation of said manual means.

4. In a feed mechanism for machine tools, a shaft, a reversible, variable speed driving element, transmission means between the driving element and the shaft, said transmission means including a differential through which the shaft is driven in feeding direction at a slow rate, means for automatically locking said differential when the driving element is reversed to drive the shaft in the reverse direction at a rapid rate without change in the rate of the driving element, a clutch between the shaft and transmission means, manual means for rotating the shaft and cam means actuated by said manual means for disengaging said clutch upon actuation of said manual means.

5. In a feed mechanism for machine tools, a stationary frame, a shaft, a pair of gears rotatably mounted on said shaft, one of said gears being coupled to the shaft, a cage mounted for rotation about said gears, connected pinions with unequal numbers of teeth carried by said cage and meshing respectively with the gears, a one-way clutch between one of said gears and the cage, an oppositely directed one-way brake between the other of the gears and the stationary frame, and means for driving the cage in reverse directions.

6. In a feed mechanism for machine tools, a stationary frame, a shaft, a pair of gears rotatably mounted on said shaft, one of said gears being coupled to the shaft, a cage mounted for rotation about said gears, connected pinions with unequal numbers of teeth carried by said cage and meshing respectively with said gears, a one-way clutch between one of said gears and the cage, means including a friction device operable to hold the clutch in or out of engagement depending upon the direction of rotation of the cage, a one-way brake between the other of said gears and the stationary frame, and means including a second friction device operable to hold the brake in engagement when the cage is revolving in a direction to cause the clutch to be disengaged and out of engagement when the cage revolves in the opposite direction.

7. In a feed mechanism for machine tools, a stationary frame, a shaft, a pair of gears rotatably mounted on said shaft, one of said gears being coupled to the shaft, a cage mounted for rotation about said gears, connected pinions with unequal numbers of teeth carried by said cage and meshing respectively with said gears, a one-way clutch between one of said gears and the cage, means including friction and lost motion devices operable to shift the clutch into or out of engagement a predetermined interval after the initiation of rotation of the cage in one direction or the other respectively, a one-way brake between the other of said gears and the stationary frame, and means including friction and lost motion devices operable to shift the brake into engagement a predetermined interval after the initiation of rotation of the cage in a direction to cause the clutch to be disengaged, and to shift the brake out of engagement a predetermined time after the initiation of rotation of the cage in the opposite direction.

ROGER S. PYNE.
